United States Patent Office

Des. 203,179

Patented Dec. 14, 1965

203,179

ENCAPSULATED ELECTRICAL COIL

James A. Foerster, Fort Wayne, Ind., assignor to Wabash
Magnetics, Inc., Wabash, Ind., a corporation of Indiana

Filed Sept. 3, 1964, Ser. No. 81,587

Term of patent 14 years

(Cl. D26—1)

Fig. 1.

Fig. 2.

Fig. 3.

FIG. 1 is a front perspective view of an encapsulated electrical coil showing my new design;

FIG. 2 is a rear elevation view thereof; and

FIG. 3 is a bottom plan view thereof.

I claim:

The ornamental design for an encapsulated electrical coil, as shown.
